UNITED STATES PATENT OFFICE.

RAY S. WILBUR, OF LYNDHURST, NEW JERSEY, ASSIGNOR TO WESTERN ELECTRIC COMPANY, INCORPORATED, OF NEW YORK, N. Y., A CORPORATION OF NEW YORK.

TELEPHONE-EXCHANGE SYSTEM.

1,281,459.

Specification of Letters Patent. Patented Oct. 15, 1918.

Application filed March 8, 1918. Serial No. 221,168.

To all whom it may concern: Be it known that I, RAY S. WILBUR, a citizen of the United States, residing at Lyndhurst, in the county of Bergen, State of New Jersey, have invented certain new and useful Improvements in Telephone-Exchange Systems, of which the following is a full, clear, concise, and exact description.

This invention relates to telephone exchange systems and more particularly to such systems of the central energy type.

The object of this invention is the provision of improved signaling means for such systems.

In accordance with this invention a link circuit having a supervisory relay and a signaling device is provided with a first relay energized upon the energization of the supervisory relay and controlling a second relay which is energized upon the subsequent deenergization of the supervisory relay and cooperates therewith upon the subsequent energization of the supervisory relay to include interrupter mechanism in circuit with the signaling device, thereby to furnish a recall signal from a connected telephone line.

For a more complete understanding of this invention reference should be had to the following description considered in connection with the accompanying drawing illustrating one embodiment thereof.

Referring to the drawing, there are shown two telephone lines, A and B, which terminate at a central office at which is located a link circuit C for interconnecting the telephone lines. It will be understood, of course, that many lines similar to A and B may and usually do terminate at the same central office and that a plurality of link circuits similar to C may be employed. For the sake of convenience, however, only the two telephone lines and one link circuit are shown.

Subscriber A in initiating a call removes the receiver from the switchhook, causing the operation of line relay 4, whereupon line lamp 5 lights. The operator observing the lighted condition of the line lamp 5, inserts answering plug 6 of cord circuit C into jack 7 of the calling line, whereupon cutoff relay 12 operates over a circuit from battery through resistance 25, sleeve contacts of the plug 6 and the jack 7 and the winding of cutoff relay 12 to ground. Cutoff relay 12

in operating disconnects line relay 4 from the line, thereby extinguishing the line lamp 5. Supervisory relay 8 is also operated, whereupon relay 9 operates over a circuit from battery through contact 13 of listening key 10, answering supervisory lamp 11, alternate contact of the answering supervisory relay 8, right-hand normal contact and left hand winding of relay 9, sleeve contacts of the plug 6 and the jack 7 and the winding of the cutoff relay 12 to ground. Relay 9 in operating completes a locking circuit for itself from battery through contact 13 of listening key 10, the right-hand winding alternate contact and the left-hand winding of relay 9, sleeve contacts of the plug 6 and the jack 7 and the winding of the cutoff relay 12 to ground. The establishment of this locking circuit renders relay 9 independent of supervisory relay 8. The operator may now actuate listening key 10 to connect the operator's telephone 8 with the cord circuit. The actuation of this listening key opens contact 13 thereof thereby interrupting the locking circuit of relay 9, which releases its armatures.

The operator upon being advised that connection is desired with the line of subscriber B, restores the listening key to normal position and inserts calling plug 15 into line jack 16. The restoration of listening key 10 to normal position causes the energization and locking up of relay 9 in the manner already described. The insertion of the calling plug 15 into jack 16 operates cutoff relay 22 which disconnects the line relay from the line. Calling supervisory lamp 18 is lighted over a circuit from battery through contact 14 of listening key 10, lamp 18, normal contact of calling supervisory relay 19, contact 20 of relay 21, sleeve contacts of the calling plug 15 and the jack 16 and the winding of cutoff relay 22 to ground. While resistance 23 is in parallel with the lamp 18 it is so high as not to affect the lighting of the lamp. The operator may now actuate a ringing key 24 to connect with the line B a source of ringing current for operating the usual call bell at the station.

Subscriber B in responding to the actuation of the call bell removes the receiver from the switchhook, thereby causing the energization of calling supervisory relay 19, extinguishing the calling supervisory lamp

18. Relay 19 in operating causes the operation of relay 21 over a circuit from battery through contact 14 of listening key 10, lamp 18, alternate contact of relay 19, left-hand 5 normal contact of relay 21, right-hand winding thereof, sleeve contacts of the plug 15 and the jack 16, and the winding of cutoff relay 22 to ground. Relay 21 in operating completes a locking circuit for itself 10 from battery through contact 14 of listening key 10, the left-hand winding and alternate contact and the right-hand winding of relay 21, sleeve contacts of the plug 15 and the jack 16, and the winding of cutoff relay 15 22 to ground. Relay 21 is thereby rendered independent of the condition of the calling supervisory relay 19.

At the conclusion of the conversation subscribers A and B restore the receivers to the 20 switchhooks, causing the release of the answering and the calling supervisory relays 8 and 19. The release of relay 8 causes the answering supervisory lamp 11 to be lighted over a circuit from battery through contact 25 13 of listening key 10, the lamp 11, normal contact of supervisory relay 8 and the middle alternate contact of relay 9 to ground. The release of the answering supervisory relay 8 also causes the energization of relay 30 26 over a circuit from battery through contact 13 of listening key 10, winding of relay 26, normal contact thereof, left-hand alternate contact of relay 9, normal contact of supervisory relay 8 and the middle alternate 35 contact of relay 9 to ground. Relay 26 in operating establishes a locking circuit for itself from battery through contact 13 of listening key 10, winding of relay 26, right-hand alternate contact thereof, sleeve contacts 40 of the plug 76 and the jack 7, and the winding of the cutoff relay 12 to ground. Relay 26 is now locked up independent of the condition of the answering supervisory relay 8. Relay 26 in operating also connects 45 an interrupter 27 through its left-hand alternate contact to the alternate contact of answering supervisory relay 28. The release of the calling supervisory relay 19 causes the calling supervisory lamp 18 to be 50 lighted over a circuit from battery through contact 14 of listening key 10, lamp 18, normal contact of relay 19, and the middle alternate contact of relay 21 to ground. Relay 28 also operates over a circuit from 55 battery through contact 14 of listening key 10, winding of relay 28, normal contact thereof, right-hand alternate contact of relay 21, normal contact of supervisory relay 19 and the middle alternate contact of relay 21 60 to ground. Relay 28 in operating establishes a locking circuit for itself from battery through contact 14 of listening key 10, winding and left-hand alternate contact of relay 28, sleeve contacts of plug 15 and jack 65 16, and the winding of the cutoff relay 22 to

ground. Relay 28 is now locked up independent of the condition of the calling supervisory relay 19. The interrupter 27 is now connected through the right-hand alternate contact of relay 28 to the alternate contact of supervisory relay 19. The lighting of the two supervisory lamps 11 and 18 serves as a disconnect signal to the operator, who may thereupon withdraw the plugs from the jacks, restoring all apparatus to 75 normal condition.

If, before the plugs are withdrawn from the jacks, the subscriber A initiates a recall, the answering supervisory lamp 11 is intermittently lighted to furnish a recall signal 80 to the operator. In initiating this recall, subscriber A removes the receiver from the switchhook, thereby causing the operation of the answering supervisory relay 8. The interrupter 27 is thereupon immediately connected in circuit with the lamp 11. This circuit may be traced from battery through contact 13 of listening key 10, the lamp 11, the alternate contact of the answering supervisory relay 8, left-hand alternate contact 85 of relay 26 and interrupter 27 to ground. The operator upon observing the intermittent lighting of the answering supervisory lamp 11 may actuate listening key 10 to connect the operator's telephone set with the 90 cord circuit. The actuation of this listening key 10 causes the release of the relays 9 and 26 associated with the answering end of the cord circuit and relays 21 and 28 associated with the calling end thereof. The release of relay 26 stops the intermittent lighting of the lamp 11. The release of relays 21 and 28 connects the lamp 18 in a circuit which includes the sleeve contacts of the plug 15 and the jack 16. 100

If it had been subscriber B who initiated the recall before the plugs were withdrawn from the jacks, the calling supervisory relay 18 would then have been intermittently lighted over a circuit from battery through contact 14 of listening key 10, the lamp 18, the alternate contact of calling supervisory relay 19, right-hand alternate contact of relay 28 and the interrupter 27 to ground. 110

What is claimed is:

1. A telephone exchange system comprising a telephone line, a link circuit connected therewith, a supervisory relay in the link circuit, a first relay, an energizing circuit therefor completed upon the energization 115 of the supervisory relay and including a contact thereof, a signaling device continuously operated upon the deenergization of the supervisory relay, a second relay, an energizing circuit therefor controlled by the first relay and established upon the deenergization of the supervisory relay while the first relay is energized and including a contact of the deenergized supervisory relay and interrupter mechanism connected in circuit 120 125 130

with the signaling device upon the subsequent energization of the supervisory relay.

2. A telephone exchange system comprising a telephone line, a link circuit connected therewith, a supervisory relay in the link circuit, a first relay energized upon the energization of the supervisory relay, a signaling device continuously operated upon the deenergization of the supervisory relay, a second relay, an energizing circuit therefor controlled by the first relay and established upon the deenergization of the supervisory relay while the first relay is energized and including a contact of the deenergized supervisory relay, an operator's telephone set, a listening switch for connecting the operator's telephone set with the link circuit, interrupter mechanism and an operating circuit for the signaling device and the interrupter mechanism established upon the deenergization and the subsequent energization of the supervisory relay and including a contact of the listening switch.

3. A telephone exchange system comprising a telephone line, a link circuit connected therewith, a supervisory relay in the link circuit, a first relay, an energizing circuit therefor completed upon the energization of the supervisory relay and including a contact thereof, a signaling device continuously operated upon the deenergization of the supervisory relay, a second relay, an energizing circuit therefor controlled by the first relay and established upon the deenergization of the supervisory relay, an operator's telephone set, a listening switch for connecting the operator's telephone set with the link circuit, interrupter mechanism, and an operating circuit for the signaling device and the interrupter mechanism established upon the subsequent energization of the supervisory relay while the second relay is energized and including a contact of the listening switch.

4. A telephone exchange system comprising a telephone line, a link circuit connected therewith, a supervisory relay in the link circuit, a first relay energized upon the energization of the supervisory relay, a signaling device continuously operated upon the deenergization of the supervisory relay, a second relay, an energizing circuit therefor controlled by the first relay and established upon the deenergization of the supervisory relay, an operator's telephone set, a listening switch for connecting the operator's telephone set with the link circuit, interrupter mechanism, and an operating circuit for the signaling device and the interrupter mechanism established upon the subsequent energization of the supervisory relay and in-

cluding a contact of the energized second relay and a contact of the listening switch.

5. A telephone exchange system comprising a telephone line, a link circuit connected therewith, a supervisory relay in the link circuit, a first relay, an energizing circuit therefor completed upon the energization of the supervisory relay and including a contact thereof, a second relay controlled by the first relay and energized upon the deenergization of the supervisory relay while the first relay is energized, a locking circuit for the second relay established upon the energization thereof for rendering this relay independent of the supervisory and first relays, a signaling device, interrupter mechanism, and an operating circuit for the signaling device and interrupter mechanism established upon the subsequent energization of the supervisory relay.

6. A telephone exchange system comprising a telephone line, a link circuit connected therewith, a supervisory relay for the link circuit, a first relay having two windings, an energizing circuit therefor including one winding established upon the energization of the supervisory relay, a locking circuit for the first relay including the other winding established upon the energization thereof, a second relay, an energizing circuit therefor including a contact of the energized first relay and a contact of the supervisory relay when deenergized, a locking circuit for the second relay independent of the supervisory and first relays established upon the energization of the second relay, a signaling device, interrupter mechanism, and an operating circuit for the signaling device and the interrupter mechanism established upon the subsequent energization of the supervisory relay and including contacts of the supervisory and second relays.

7. A telephone exchange system comprising a telephone line, a link circuit connected therewith, a supervisory relay in the link circuit, a first relay, an energizing circuit therefor completed upon the energization of the supervisory relay and including a contact thereof, a second relay, an energizing circuit therefor controlled by the energized first relay and established upon the closure of a contact of the supervisory relay when deenergized, a signaling device, interrupter mechanism, and an operating circuit for the signaling device and the interrupter mechanism controlled by the second and supervisory relays.

In witness whereof, I hereunto subscribe my name this 21st day of February, A. D., 1918.

RAY S. WILBUR.
